CLAIM

The ornamental design for a wall mountable bathing pillow, as shown and described.

DESCRIPTION

FIG. 1 is a left, top, front perspective view of a wall mountable bathing pillow embodying our new design;

FIG. 2 is a front elevational view thereof;

FIG. 3 is a top plan view thereof;

FIG. 4 is a left side elevational view, the right side elevational view being a mirror image of the left side shown;

FIG. 5 is a bottom view thereof; and,

FIG. 6 is a rear view thereof.

The broken line showing of suction cups in FIGS. 4 and 6 are for purposes of illustration only and forms no part of the claimed design.
